Primary Examiner—Ruth McInroy(74) *Attorney, Agent, or Firm*—Goodwin Procter LLP(57) **CLAIM**

The ornamental design for a dust collector, as shown and described.

DESCRIPTION

FIG. 1 is a perspective view of the dust collector.

FIG. 2 is a top view thereof.

FIG. 3 is a bottom view thereof.

FIG. 4 is a rear elevational view thereof.

FIG. 5 is a front elevational view thereof.

FIG. 6 is a right side elevational view thereof; and,

FIG. 7 is a left side elevational view thereof.

1 Claim, 6 Drawing Sheets# US D573,615 S
